INVENTOR:

Greenleaf V. Luce

UNITED STATES PATENT OFFICE.

GREENLEAF V. LUCE, OF INDIANAPOLIS, INDIANA.

IMPROVEMENT IN TRUNK-LOCKS.

Specification forming part of Letters Patent No. 222,359, dated December 9, 1879; application filed June 10, 1879.

To all whom it may concern:

Be it known that I, GREENLEAF V. LUCE, of the city of Indianapolis, county of Marion, and State of Indiana, have invented certain new and useful Improvements in Trunk-Locks, of which the following is a specification, reference being had to the accompanying drawings, which are made a part hereof, and on which similar letters of reference indicate similar parts.

Figure 1 is a front elevation of my improved lock and the supplemental locking devices connected therewith. Fig. 2 is an elevation of the reverse side of the lock. Fig. 3 is a view of the reverse side of a portion of the front lock-plate with the lock mechanism removed. Fig. 4 is a front elevation of the operating mechanism of the lock. Fig. 5 is a side elevation of the same. Fig. 6 is a transverse and nearly horizontal section of the lock mechanism and adjacent parts on the dotted line $\alpha\alpha$ in Figs. 1 and 4. Fig. 7 is a side elevation of the key which operates my improved lock.

In said drawings, the portions marked A represent the catch, which is placed upon the cover of the trunk, chest, or other similar article, to engage with the lock; A' A², similar catches to engage with the supplemental locking devices; B, the front plate of the main lock, which, with the rear plate, L, incloses the lock mechanism; C, the device with which the key engages, and through which said key operates the lock-bolts; D, the lock-bolt of the main lock; D' D², the lock-bolts of the supplemental locking devices; E E, rods which connect the bolts D' D² to the bolt D; F, a spring-seated locking-pin, which engages in a corresponding recess, m, in the inner side of the plate B, and thus prevents the device C from turning except when this pin is pushed back by the key in locking or unlocking the lock; G, the spring against which the pin F rests; H, the key, which is bored out to fit over the stem c on the device C. It is also cut away at the side at f to fit the pin F, and has a projection, k, which engages in the notch k' in the device C, thereby turning said device, and, through the connection shown in

Fig. 2, moving the bolt D, and, through the rods E E, the supplemental bolts D' D².

The hooked portions of the catches A A' A² are marked a a' a². The projecting portion of the plate B, which comes through the wall of the trunk to the outside, and in which is the key-hole, is marked b. The wall of the trunk surrounding the lock is marked N.

In this lock it will be noticed that all the parts are very strong and simple, that the movement of the locking-pin F is transverse to that of the lock-bolt D, and that therefore no jar of the bolt or catch can disturb the engagement of said pin, and that the distance between the pin F and recess k' must be identical with that between the notch f and projection k on the key; otherwise the key could not fully enter the lock; and as the distance may be varied a large number of times before again reaching the same relative positions as at first, a large number of locks may be made in which none of the keys will fit any other than its own lock.

The object of my invention is to provide a cheap and simple, but at the same time strong and secure, locking attachment for trunks, chests, packing-boxes, tool-chests, &c., and this object is attained by the construction and arrangements of parts hereinbefore described.

Having thus fully described my said invention, what I claim as new, and desire to secure by Letters Patent, is—

The combination of the plate B, recessed at b for the reception of the device C, and having in the side of the recess b the smaller recess, m, for the reception of one side of the transversely-moving bolt F, the device C, having stem c, spring-seated bolt F, and notch k', the trunk-key H, having a projection, k, and a recess, f, and the lock-bolt and catch mechanism, all substantially as shown and specified.

In witness whereof I have hereunto set my hand and seal at Indianapolis, Indiana, this 25th day of June, A. D. 1879.

GREENLEAF V. LUCE. [L. S.]

In presence of—

C. BRADFORD,
W. L. CORNELIUS.
